Primary Examiner — Janice Seeger(74) *Attorney, Agent, or Firm* — Frost Brown Todd LLC(57) **CLAIM**

The ornamental design for a table base, as shown and described.

DESCRIPTION

FIG. 1 is a perspective view of a table base, showing my new design;

FIG. 2 is a perspective view showing the table base in an alternate environment;

FIG. 3 is a perspective view of a table base, showing an alternate embodiment of my new design; and,

FIG. 4 is perspective view showing the table base in a folded condition.

Portions of the accompanying drawings that appear in phantom lines do not form part of the invention as claimed.
